UNITED STATES PATENT OFFICE

169,038

COASTER WAGON

Marion Louis Hall, Elgin, Ill.

Application January 30, 1952, Serial No. 18,310

Term of patent 7 years

(Cl. D34—15)

To all whom it may concern:

Be it known that I, Marion Louis Hall, a citizen of the United States, residing at Elgin, State of Illinois, have invented a new, original, and ornamental Design for a Coaster Wagon, of which the following is a specification, reference being had to the accompanying drawings, forming a part hereof.

Fig. 1 is a perspective view of a coaster wagon, showing my new design;

Fig. 2 is a side view of the coaster wagon;

Fig. 3 is a plan view thereof;

Fig. 4 is a back view thereof.

I claim:

The ornamental design for a coaster wagon, as shown.

MARION LOUIS HALL.
